[57] CLAIM

The ornamental design for a door lever, as shown and described.

DESCRIPTION

FIG. 1 is a front elevation of a door lever showing my new design;

FIG. 2 is a rear elevation view thereof;

FIG. 3 is a top plan view thereof;

FIG. 4 is a bottom plan view thereof;

FIG. 5 is an end elevation view thereof;

FIG. 6 is an elevation view of the opposite end thereof; and,

FIG. 7 is an elevation view similar to that shown in FIG. 1 with the design shown in a different orientation.

FIG. 7

FIG. 2

FIG. 3

FIG. 4

FIG. 5

FIG. 6

FIG. 1
